UNITED STATES PATENT OFFICE.

JOSEPH F. JOY, OF NEW BETHLEHEM, PENNSYLVANIA, ASSIGNOR TO JOY MACHINE COMPANY, OF PITTSBURGH, PENNSYLVANIA, A CORPORATION OF DELAWARE.

DRILL.

Application filed February 18, 1919. Serial No. 277,837.

To all whom it may concern:

Be it known that I, JOSEPH F. JOY, a citizen of the United States of America, residing at New Bethlehem, in the county of 5 Clarion and State of Pennsylvania, have invented certain new and useful Improvements in Drills, of which the following is a specification.

This invention relates to certain new and 10 useful improvements in drills, and is especially designed to form shot holes in coal veins.

When electric power was adopted in coal mines in lieu of compressed air, electric 15 motor driven coal drills naturally came into use. It was soon found that the choking or sticking of the drill bits overloaded and burned out the electric motors instead of merely stalling the same with no ill after 20 effects as had been the case with air motors. With a view to overcome this trouble of burned out electric motors, the manufacturers of electric coal drills increased the strength of their products and consequently 25 the weight thereof to such an extent that electric coal drill operation became a two man proposition. It is the primary object of the present invention, therefore, to produce "a one man electric coal drill" by incorporating 30 protective and power conserving features therein which permit the use of light parts.

In using a feed screw or rack to form a six foot hole, it would require the use of a 35 six foot auger or bit therewith, which, including the other necessary mechanism, would make a gross length for the drill of about fourteen feet. The presence of mine timbering up to within eight or ten feet of 40 the face of the vein in most mines will not permit the use of a machine of such undue length and in order to overcome this defect, the feed screw or rack was made to have only about a two-foot feeding capacity thus 45 requiring a change from short to longer augers or bits every two feet. Another reason for the present necessary use of short drill bits and short feed screws or stems, is the absence of some means to prevent "slopping" or wabbling of the drill out of true 50 under the feed pressure especially when the feed action is positive. It is a further object of the invention, therefore, to provide a force feed drill of telescopic construction so

as to occupy a minimum amount of space 55 lengthwise and thereby permit the use of a full length bit or auger to expedite the drilling operation by overcoming the necessity of changing the drill bits.

A further object of the invention is to 60 greatly lessen the cost and weight of devices of this kind and at the same time also improve the practicability and durability thereof.

A still further object of the invention is 65 to provide a coal drill which is so operated that destruction of mechanism or breaking of the auger or bit is extremely unlikely.

With the above general objects in view and others that will become apparent as the 70 nature of the invention is better understood, the same consists in the novel form, combination and arrangement of parts hereinafter more fully described, shown in the accompanying drawings and claimed. 75

In the accompanying drawings forming part of this specification, and in which like reference characters indicate similar parts throughout the several views,

Figure 1 is a top plan view of a drill constructed in accordance with the present invention, 80

Fig. 2 is a side elevational view of the device shown in Fig. 1, partly broken away, and illustrated in operative position in a 85 mine room,

Fig. 3 is a transverse sectional view of the drill taken substantially on line III—III of Fig. 1, and showing in dotted lines and by arrows the tendency of the motor to turn 90 over when the bit sticks or chokes,

Fig. 4 is a transverse sectional view of the drill taken substantially on line IV—IV of Fig. 1,

Fig. 5 is a fragmentary enlarged detail 95 view, partially in section and partially in elevation, taken substantially on line V—V of Fig. 1,

Fig. 6 is an enlarged fragmentary detail view, partly in section and partly in elevation, taken substantially on line VI—VI of Fig. 1, 100

Fig. 7 is a fragmentary plan view showing a modification of a portion of the device shown in Fig. 1, and

Fig. 8 is a side elevational view of the device shown in Fig. 7, partly broken away. 105

Referring more in detail to the several

views, the device includes an open elongated rectangular frame formed of end members 9 and side members 10, preferably of tubular form and joined at the corners of the 5 frame by L-couplings 11.

Arranged between the side members 10, is a suitable motor 12, preferably electrical, which is controlled by the switch 13 and which is movable longitudinally of the frame 10 in order to move with the drill bit 14 when the latter is fed to its work. The motor is slidably mounted for movement longitudinally of the frame by means of sleeves 15 carried by the opposite sides thereof and 15 loosely encircling the side members 10 of the frame.

It is usual, in drilling shot holes, to drill the same a depth equal to the thickness of the vein and heretofore this has been done 20 by first drilling part way by a short drill bit and then successively substituting longer bits until the necessary depth has been attained. This has been necessary in order to prevent the longest bit from breaking as the same 25 would not be properly supported and braced against breaking strains, when beginning to drill the hole with prior constructions. In order to avoid the delays caused by the above, I have provided guides or braces 16 30 and 17 which loosely surround the bit 14 so that a single long bit is used to drill the entire hole. The guide 16 is of tubular form and is rigidly positioned at the forward end of the frame between the members 9 thereof 35 as shown in Figs. 1 and 7. The motor casting is provided with handles 12' for the purpose of drawing the bit from the hole or moving it back and forth therein to clear the hole when serious choking occurs.

40 Arms 18 extend from opposite sides of the guide 17 transversely of the frame and are provided on their outer free ends with sleeves 19 which loosely embrace the side members 10 so that said guide 17 may be 45 moved toward or away from the guide 16.

Projecting laterally from the sleeve 15 at one side of the frame is a lug 20 to which one end of a flexible member or cable 21 is fastened, said cable extending forwardly to 50 and around pulleys 22 carried by the lugs 23 extending from the couplings 11 at the forward end of the frame. The cable 21 is then extended rearwardly to a drum 24 journaled on a stub shaft 25 carried by the adjacent sleeve 15 so that, by rotating said drum, in one direction, through the instrumentality of handle 26, the cable 21 is wound upon the drum and thereby causes motor 12 and bit 14 to move forwardly toward the work. 55

60 It is to be understood that bit 14 is secured to or geared to the armature shaft of motor 12 as is usual in this type of device and that motor 12 will move forwardly to engage guide 17 and then slide the latter along toward the guide 16.

In practice, the bit 14 often becomes overloaded or stuck and if the same is caused by positive means to continue feeding into the work under this condition, the said bit will be broken or the motor overloaded unless 70 extremely bulky and heavy. By providing the hand feed above described, the operator can "feel" the tendency of the bit to stick and immediately cease feeding, lessen the speed of feeding, or may clean the hole 75 by sliding the drill bit in and out of the same by means of handle 12' thereby avoiding breakage of the bit and enabling one to use comparatively light and cheap parts in the drill. 80

It has also been found that a five and one half horse-power motor must be used in order to insure driving of the heavy bit when inclined to stick in order to prevent the motor from being burned out or when 85 using a construction such as would prevent the apparatus from "kicking over" as illustrated in Fig. 3. By feeding by hand as above described, I substantially entirely 90 avoid the sticking of the drill and therefore am enabled to use a comparatively light and cheap motor of one horse-power capacity. 95

However, if, through fault of the operator, the drill bit becomes stuck, I avoid the breakage of said bit or burning out of the 95 motor by pivotally mounting the frame on a pin 27 so that the same together with the motor 12 may turn over as shown in Fig. 3. With this construction the reaction of the overload of the motor tends to revolve the 100 frame in a direction opposite to the direction of rotation of the drill, and as the feed drum is carried by the frame, the operator will receive warning that the rate of feed is too great or that the bit is choking. The 105 pin 27 is rigid with a bracket 28 and extends through the sleeve 29 carried by the rear end of the frame, said pin being retained therein by a suitable cotter pin 30.

The bracket 28 is pivoted for vertical 110 movement as at 31 to the sleeve 32 and the sleeve 32 is slidable on the shank of the screw jack post 33, a suitable set screw 34 being provided in order to retain the sleeve 32 in any of its adjusted positions on said jack post. By this arrangement, the frame 115 may be supported at any desired height at its rear end and may be swung vertically to the desired elevation at its forward end. 120

In starting to drill a shot hole, it is often desirable to provide a means to support the forward end of the frame, and in Figs. 7 and 8 I have shown a modification of the device shown in the other figures having props for this purpose. In this form of the device, the members 9 and 10 are joined by three-way couplings 11'; each of which has a rod 35 swivelled therein as at 36. The rods 35 have integral sleeves 37 through which are slidably positioned the props 38 130

having heads 39 to prevent said props from moving downwardly entirely through said sleeves. The props 38 are extended to pointed ends in accordance with the form of the 5 lower portion of jack 33 as seen in Fig. 2. The rods 35 are swiveled so that the props may be set at any desired inclination and suitable pins may be placed through any one of the perforations 40 of the props to 10 support the forward end of the frame at the desired height. In this form of the invention, the pulleys 22 are supported by brackets 23' clamped to the side members 15 adjacent the couplings 11'.
 15 In operation, the device is set up as shown in Fig. 2, and the motor is started. The operator then rotates drum 24 and thereby feeds the drill until the hole is cut the required depth.
 20 It is believed that the construction and operation of the present invention as well as the advantages thereof will be readily understood by those skilled in the art from the foregoing description, and while the 25 forms of the invention herein shown and described are what are believed to be the preferred embodiments thereof, it is nevertheless to be understood that minor changes may be made in the form, combination, and 30 arrangement of parts without departing from the spirit and scope of the invention as claimed.

What I claim as new is:—

1. A drill comprising an open elongated 35 frame including side and end members, a motor arranged between and supported by the side members for movement longitudinally of the frame, a drill bit extending longitudinally of the frame and projecting 40 beyond the forward end thereof, said bit being rotatable by said motor, means to move said motor forwardly to feed the drill bit to its work, a stationary guide for said drill bit at the forward end of the frame, 45 and a second transverse rear guide for said drill bit supported by said side members for movement longitudinally of the frame, said second guide being forwardly movable by said motor.
 50 2. A drill comprising a frame, a motor movable longitudinally of the frame, a drill bit rotatable by the motor, a stationary guide for the bit carried by the forward end of the frame, and a second transverse 55 rear guide for the bit movable longitudinally of the frame, said second guide being

forwardly movable by engagement of said motor therewith.

3. A drill comprising an open elongated frame including side and end members, a 60 motor arranged between and supported by the side members for movement longitudinally of the frame, a drill bit extending longitudinally of the frame and projecting beyond the forward end thereof, said bit being 65 rotatable by said motor, means to move said motor forwardly to feed the drill bit to its work, and a transverse guide for said drill bit supported by said side members for movement longitudinally of the frame, said 70 guide being forwardly movable by said motor.

4. A drill comprising a frame, a motor movable longitudinally of the frame, a drill bit rotatable by the motor, and a guide for 75 the bit movable by said motor longitudinally of the frame.

5. A drill comprising an upright supporting means, a frame pivoted at its rear end to said supporting means for vertical swinging movement, a drill bit, means carried by said frame to rotate said bit, means including props associated with the forward end of the frame to support the same in vertically adjusted positions, said props being 85 swivelly connected to the frame whereby the same may be placed at a desired inclination.

6. A drill comprising an open elongated frame including side and end members, a motor arranged between and supported by 90 the side members for movement longitudinally of the frame, a drill bit extending longitudinally of the frame and projecting beyond the forward end thereof, said bit being operatively connected to said motor, 95 means to move said motor to feed the drill bit to its work, and a support pivotally connected to the rear end of said frame whereby the latter together with the motor may axially rotate when the bit becomes overloaded or stuck.

7. A drill comprising a frame, a motor movable longitudinally of the frame, a drill bit rotatable by the motor, and a support to which the rear end of said frame is pivoted whereby the latter together with the motor may axially rotate relative to said support when the bit becomes overloaded or stuck.

In testimony whereof I affix my signature.

JOSEPH F. JOY.
